Atty.

UNITED STATES PATENT OFFICE.

CHARLES MÜLLER, OF ZURICH, SWITZERLAND.

HATCHING INSTRUMENT FOR DRAWINGS.

1,362,635.

Specification of Letters Patent. Patented Dec. 21, 1920.

Application filed February 24, 1920. Serial No. 360,872.

To all whom it may concern:

Be it known that I, CHARLES MÜLLER, a citizen of the Republic of Switzerland, residing at Zurich, Switzerland, have invented 5 certain new and useful Improvements in Hatching Instruments for Drawings; and I do hereby declare the following to be a clear, full, and exact description of the invention, such as will enable others skilled 10 in the art to which it appertains to make and use the same, reference being had to the accompanying drawing, and to letters or figures of reference marked thereon, which form a part of this specification.

15 The present invention relates to drawing instruments and more particularly to instruments used for hatching parts of drawings.

In the accompanying drawing which 20 shows one mode of carrying this invention into effect,

Figure 1 is a plan,

Fig. 2 is a vertical section along line A—B of Fig. 1.

25 Fig. 3 shows the instrument connected to a T-square.

1 denotes a plate on which two friction wheels 4 and 5 are rotatably mounted on bolts 2 and 3 respectively, the wheels being 30 provided with teeth on their circumference for the purpose of producing friction. The teeth of the wheels project over one of the longitudinal edges of plate 1. A ratchet wheel 6 is mounted on bolt 2, the ratchet wheel 6 and the friction wheel 4 being connected to each other by means of a dowel pin 7 fixed in the toothed wheel 4 and projecting into a hole of the ratchet wheel 6, the two wheels 4 and 6 turn together. Further 35 a two-armed lever 8 is mounted on bolt 2 acting as fulcrum, which carries on one arm a spring loaded pawl 9 that is in engagement with the ratchet wheel 6, and on the other arm a tension spring 10 which tends to keep the opposite arm of the lever 40 pressed against a stud 11. One arm of the lever is bent upward and ends in a key 12, which projects above the upper longitudinal edge of plate 1. 13 denotes a milled 45 edge thumb screw mounted on the plate by which the stroke of the lever 8 can be regulated.

The instrument described is shown in Fig. 50 3 connected to a T-square 14, 15. It is screwed to the underside of the head 14 of a T-square by means of screws going through

the holes 16 of plate 1 and it is placed, with reference to the head 14, so that the longitudinal edge of plate 1, over which the teeth of the wheels 4 and 5 project, is flush with 60 the inner edge of the head 14. The angle between the edge of the blade of the T-square and the inner edge of the head 14 can be altered and the two parts fixed against each other by means of a clamping screw 65 17. A slot 18 is provided in the plate 1 for allowing screw 17 to pass through the plate 1.

In order to hatch a part of a drawing with this instrument fixed to the T-square, 70 key 12 is to be pressed down after a line is drawn until the lever 8 rests against the set screw 13. Thereby the wheel 4 is turned by means of the pawl 9 engaging the ratchet wheel, which turning motion of wheel 4 75 causes part of its circumference to roll on the edge of the drawing board, the teeth of the wheel penetrating into the edge of the board and preventing any gliding. The rolling motion of the wheel 4 causes a parallel translation of the T-square and a new 80 line may be drawn on the drawing board.

The turning of the blade of the T-square against the head round screw 17 to almost 85 any given angle allows of producing hatchings at almost any angle with the horizontal line. The distance between the parallel lines can be altered by adjusting the thumb-screw 13. Such an alteration may also be attained by interchanging ratchet wheel 6 90 with another of different pitch.

A spring loaded pawl 19, locking the ratchet wheel 6 when the lever is at rest, is provided on the opposite side of pawl 9, which prevents an unintended displacement 95 of the T-square along the edge of the board in the direction in which pawl 9 does not lock. Pawl 19 is brought out of engagement with the ratchet wheel when the key 12 is 100 pressed down and the wheel is thus free to 105 the ratchet action caused by the pawl 9.

A hatching instrument according to the present invention may be quickly and easily 110 fixed to any T-square and a drawing of large dimensions may be hatched without damaging the drawing. This is a great advantage over the hitherto known constructions, wherein toothed wheels or needle points work on the drawing itself and damage it. The new instrument is not so easily displaced through inattention as the existing constructions. With the latter such dis-

placements occur very frequently because these instruments rest on the drawing and must be held in position by hand.

The known hatching instruments are moreover expensive and no large surfaces can be hatched with them, whereas the instrument according to the invention is very simple in design and can be manufactured at a low price.

10 I claim:

1. A hatching instrument, comprising a plate adapted to be fixed to the underside of the head of a T-square, friction wheels mounted on said plate and adapted to engage with the edge of a drawing board, a ratchet wheel operatively connected to one of said friction wheels, a pawl engaging the ratchet wheel, a spring loaded lever acting on the pawl, and a key integral with the lever, each movement of which causing a certain turn of the friction wheels and therefore a certain parallel translation of the parts to which the instrument may be connected.
- 15 2. A hatching instrument, comprising a plate adapted to be fixed to the underside of the head of a T-square, friction wheels mounted on said plate and adapted to engage with the edge of a drawing board, a ratchet wheel operatively connected to one of said friction wheels, a pawl engaging the ratchet wheel, a two armed lever carrying the pawl, one arm of the lever being arranged as a key, each movement of which causing a certain turn of the friction wheels and therefore a certain parallel translation of the parts to which the instrument may be connected.
- 20 3. A hatching instrument, comprising a plate adapted to be fixed to the underside of the head of a T-square, friction wheels mounted on said plate and adapted to engage with the edge of a drawing board, a ratchet wheel operatively connected to one of said friction wheels, a pawl engaging the ratchet wheel, a lever acting on the pawl, a set screw, the adjustment of which limits

the action of the lever on said pawl, and a key integral with the lever, each movement of which causing a certain turn of the friction wheels and therefore a certain parallel translation of the parts to which the instrument may be connected.

4. A hatching instrument, comprising a plate adapted to be fixed to the underside of the head of a T-square, friction wheels mounted on said plate and adapted to engage with the edge of a drawing board, an interchangeable ratchet wheel operatively connected to one of said friction wheels, a pawl engaging the ratchet wheel, a lever acting on the pawl and a key integral with the lever, each movement of which causing a certain turn of the friction wheels and therefore a certain parallel translation of the parts to which the instrument may be connected.

5. A hatching instrument, comprising a plate adapted to be fixed to the underside of the head of a T-square, friction wheels mounted on said plate and adapted to engage with the edge of a drawing board, an interchangeable ratchet wheel operatively connected to one of said friction wheels, a pawl engaging the ratchet wheel, a two armed lever provided with a key, a pawl fixed to one arm of the lever and engaging with said ratchet wheel, and a second pawl fixed to the other arm of said lever, each movement of the key causing a certain turn of the friction wheels and therefore a certain parallel translation of the parts to which the instrument may be connected.

6. A hatching instrument comprising a plate for connection to the head of a T-square, a rotatable friction member mounted on the plate adapted to engage the edge of a drawing board, a ratchet wheel operatively connected to the friction member and a lever for operating the ratchet wheel.

In testimony that I claim the foregoing as my invention, I have signed my name.

CHARLES MÜLLER.
